STANLEY SWITLIK, OF TRENTON, NEW JERSEY, ASSIGNOR TO THE SWITLIK PARACHUTE AND EQUIPMENT COMPANY, INC., OF TRENTON, NEW JERSEY, A CORPORATION OF NEW JERSEY.

REENFORCING FOR PARACHUTE SHROUD CORDS

Application filed September 25, 1931. Serial No. 565,172.

Experience shows that shroud cords tear loose from the material of which a parachute is made, and this occurs more frequently when the material of the parachute is deteriorating or getting old, therefore it is the purpose of the present invention to lessen the frequency of the shroud cords tearing away. To accomplish this it is the aim to use a reenforcing, which may be of any shape or of any size and having its original or starting point immediately adjacent the edge of the canopy parachute and to overlie the seam between the segments of the parachute, and where the reenforcing terminates immediately adjacent the edge of the parachute having a multiple of stitching to render the same secure, and a multiple of stitching through the reenforcing and through the shroud cord where it passes through the seam and under the reenforcing, thereby preventing tearing away of the shroud cord.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view of a portion of a parachute, at a part where two segments of the parachute connect, showing the application of the reenforcing at this point.

Figure 2 is a view of a portion of the parachute where the two segments unite by a seam, the same as in Figure 1, but showing the reenforcing spaced apart and unattached, but about to be attached, showing how the segments appear without the reenforcing.

Figure 3 is a longitudinal sectional view on line 3—3 of Figure 1.

Figure 4 is a sectional view on line 4—4 of Figure 1.

Referring to the drawings 1 and 2 identify portions of two segments of a parachute, and 3 the seam between the two segments. This seam comprises the segments overlapping,

the space between the stitching 4 receiving the shroud cord 5, which extends throughout the entirety of the seam to the apex of the parachute, the shroud cord previous to its location in this manner having been 55 stretched its fullest extent.

Prior to the advent of this reenforcing a multiple of stitching (not shown) has been used back and forth over the shroud cord and through the seam at a point adjacent the 60 marginal edge of the parachute, and with this mode of attaching the shroud cord, tearing away of the cord frequently occurs.

The reenforcing, though it may be of any shape and of any size is preferably of V contour, a plurality of stitching 6 passing through the reenforcing 7 adjacent the edge of the parachute. The stitchings 6 are in addition to the usual stitching 8, which makes the hem 9 at the edge of the parachute. Additional stitching 10 is carried through the reenforcing and through the opposite edges of the seam between the two segments. A multiple of stitchings 11 are made or traced back and forth through the seam and through the shroud cord, thereby making a permanent attachment of the cord, not only through the seam but also through the reenforcing, which not only provides a permanent attachment of the cord to the parachute adjacent its marginal edge, but renders the tearing away of the cord less frequent, in fact reduces the tearing away of the cord to a minimum practically nil. Rows of stitchings 12 and 13 adjacent the angle-edges 14 of the reenforcing, 80 additionally secure the reenforcing to the opposite segments of the parachute, which also reinforces the segments relative to each other. The shroud cords extend down from the edge of the parachute and are connected in the 85 usual manner (not shown) to a parachute harness (not shown).

The invention having been set forth, what is claimed is:

1. In a parachute, the combination with a 95 seam between two segments of the parachute having a hem at its edge, of a reenforcing fastened to the hem at the edge of the parachute and overlying the seam for a substantial distance, and means for attaching the 100

reenforcing over the hem, and a multiple of stitching passing through the reenforcing through the seam and back and forth through the shroud cord, for a distance substantially away from the edge of the parachute.

- 5 2. In a reenforcing for a parachute shroud cord, the combination with a seam between two segments of the parachute having a hem at its marginal edge, of a shroud cord engaged through the seam, a substantially broad re-enforcing having its origin at and stitched to the hem and stitched at its edge to the two segments of the parachute, and a multiple of stitches passing back and forth through the 10 seam and back and forth through the shroud cord and having their origin at the edge of the hem and extending from the edge of the hem and terminating at a point substantially away from the edge.
- 15 3. In a reenforcing for a parachute shroud cord, the combination with a seam between two segments of the parachute having a hem at its marginal edge, of a shroud cord engaged through the seam, a substantially broad re-enforcing having its origin at and stitched to the hem and stitched at its edge to the two segments of the parachute, and a multiple of stitches passing back and forth through the 20 seam and back and forth through the shroud cord and having their origin at the edge of the hem and extending from the edge of the hem and terminating at a point substantially away from the edge, and rows of stitches passing through the reenforcing and 25 through the seam and extending from the edge of the hem and on each side of the seam to a point substantially away from the edge of the seam.
